UNITED STATES PATENT OFFICE.

HARRY F. ROACH, OF ST. LOUIS, MISSOURI.

INSULATED RAIL-JOINT.

1,258,250.

Patented Mar. 5, 1918.

Application filed January 11, 1917. Serial No. 141,821.

To all whom it may concern:

Be it known that I, HARRY F. ROACH, a citizen of the United States, residing at St. Louis, Missouri, have invented a certain new and useful Improvement in Insulated Rail-Joints, of which the following is a full, clear, and exact description, such as will enable others skilled in the art to which it appertains to make and use the same.

10 This invention relates to insulated rail joints, and has for its main object to provide an inexpensive insulated rail joint that can be supported by a single track tie or bearing between track ties, and which is so designed that the rails which rest upon it have the effect of being hinged to the joint at the center of the joint.

Another object is to provide an insulated rail joint which is so constructed that there is no liability of the sole plate or piece of insulating material on which the base flanges of the rails rest creeping or moving longitudinally of the joint. Other objects and desirable features of my invention will be 25 hereinafter pointed out.

Figure 1 of the drawings is a side elevational view, partly broken away, of an insulated rail joint constructed in accordance with my invention.

30 Fig. 2 is a top plan view of said rail joint, partly broken away.

Fig. 3 is an end elevational view of the joint.

Fig. 4 is a vertical cross-sectional view of 35 the joint.

Fig. 5 is a detail view, illustrating a slight modification of my invention.

Fig. 6 is a perspective view of the sole plate; and

40 Fig. 7 is a view, partly in end elevation and in vertical cross section, illustrating another form of my invention.

Referring to Figs. 1 to 4 of the drawings, which illustrate the preferred form of my invention, A designates a metal member arranged on one side of the rails and provided with a base plate 1 that extends underneath the base flanges of the rails, said base plate 1 being of approximately the same length as the width of the tie B on which the joint rests and being integrally connected to the part 2 of the member A by a web 3, shown in Fig. 4, of substantially the same length as the base plate or base portion 1 of the joint. The base plate 1 is provided on its top face and at approximately its center

with a flat surface 4, and the remaining portions of the top face of said base plate are inclined downwardly in opposite directions from said flat surface 4, as shown in Fig. 1, 60 The under side of the base plate 1 is flat or parallel throughout its entire length with the flat surface 4 on the top side of said base plate, so that the member A will bear squarely and evenly upon the track tie B. 65 The portion 2 of the member A that extends longitudinally of the rails is considerably longer than the base plate 1, and said portion 2 is so designed that the intermediate part of the same will bear snugly upon the 70 insulation that is interposed between the same and the top faces of the base flanges of the rails, and thus securely clamp the rails down upon the flat rail-supporting surface 4 at the center of the base plate. 75 The ends of the portion 2 are spaced away from the base flanges and the under side of the heads of the rails sufficiently to permit the rails to deflect and move vertically slightly under load. At the upper edge of 80 the portion 2 of the member A is a thickened portion or flange 5 that extends longitudinally alongside the heads of the rails, and on the outer side of the portion 2 are oppositely-inclined braces 6 that extend 85 from the base plate 1 to the thickened portion or flange 5 at the upper edge of the portion 2 of the member A. A member C that is arranged on the opposite side of the rails, as shown in Figs. 3 and 4, co-operates 90 with the member A to hold the rails in longitudinal alignment with each other, said members A and C being connected together by means of bolts 7 that extend transversely through the same and through the webs of 95 the rails, as shown in Figs. 2, 3 and 4.

The metal members A and C of the joint are insulated from the rails by a sole plate D or flat piece of insulating material that is interposed between the base flanges of the rails and the base plate 1 and side insulating members E and F that are interposed between the rails and the members A and C, respectively, the member E being so formed that it will prevent any part of the portion 100 2 of the member A from contacting with the rails, and the insulating member F being so formed that it will prevent any part of the member C from contacting with the rails, the abutting ends of said rails being separated by the usual insulating end post (not shown). The bolts 7 are insulated from the 110

members A and C of the joint by means of tubular-shaped insulating members 8 arranged in the bolt openings and provided at their outer ends with laterally-projecting flanges or head portions 9 that serve to insulate the heads and the nuts on the bolts from the members A and C of the joint. In order to prevent the sole plate D from creeping or shifting longitudinally of the joint, I have provided said sole plate at one of its side edges with an upwardly-projecting flange 10, as shown in Fig. 6, that fits in a pocket in the member A which comprises end walls 11, as shown in Fig. 2, that serve as stops or abutments against which the opposite ends of the flange 10 on the sole plate bear. In the form of my invention shown in Figs. 1 to 4, inclusive, the end walls 11 of said pocket are formed by lugs on the web 3 of the member A. It is immaterial, however, so far as my broad idea is concerned, what means is used on the member A to prevent creepage or longitudinal movement of the sole plate, so long as the member A is formed in such a manner that a portion or portions on the same engage the upwardly-projecting flange 10 on the sole plate in such a manner that said sole plate cannot creep or move longitudinally of the joint. In the form of my invention shown in Fig. 5 the parts 11^a of the member A that serve as stops or abutments for the flange 10 on the sole plate are extended downwardly and integrally connected with the base plate 1, so as to serve as gussets which reinforce and strengthen the member A at the point where the portion 2 of the same is connected to the base plate 1. The side insulating members E and F are preferably provided with elongated holes 12 for the bolts 7, so as to permit the rails to expand and contract without causing the bolts 7 to exert pressure on the members E and F, and thus crack or break said members.

By using a side member A of the form shown and providing the top face of the base plate of the joint with a flat supporting surface 4 and sloping the remaining portions of said top face downwardly away from said supporting portion, I produce a joint in which only the ends of the rails normally rest on the joint. In other words, the rails are practically hinged to the joint at the center of the joint, and consequently, when the joint is in service, the wave motion of the rails throughout the entire track is continued uniformly through all of the joints, thereby causing the deflection throughout the entire track to be practically equal. The joint can be made as strong and stiff as desired without liability of causing the joint to break the rails or the rails to break the joint, as no portions of the joint bear against the under sides of the heads of the rails and the joint is so designed as to permit the rails to deflect within the joint at the ends of the joint, the joint merely serving to hold the abutting rails in longitudinal alignment with each other and to hinge the two rails together in such a way that the rails can deflect under load without liability of rocking the tie that supports the joint. A rail joint of the construction above described is much shorter than the insulated rail joints now in general use; it weighs considerably less than said joints and it can be manufactured at a low cost. In addition to having the desirable features above pointed out, it is so constructed that there is no possibility of the sole plate or base plate insulating member creeping longitudinally of the joint or the side insulating members being cracked or broken when the rails expand and contract. If desired, the end portions 10^a of the sole plate D can be flanged downwardly, as shown in Figs. 1 and 6, so as to bear against the side edges of the base plate, and thus hold the sole plate straight.

While I prefer to use a one-piece base plate that is integrally connected to one member of the joint, as shown in Figs. 1 to 4, this is not essential, for if desired, the joint could be formed from two metal members A' arranged on opposite sides of the rails, as shown in Fig. 7, and each provided with a base portion 1^a having a top face of substantially the same form as the top face of the base plate 1, shown in Figs. 1 to 4, thus forming a longitudinally-divided base plate or supporting portion for the rails.

Having thus described my invention, what I claim, and desire to secure by Letters Patent, is:

1. An insulated rail joint having a metal base plate of less length than the portion of the joint that extends alongside of the rails, said base plate being provided on its top face with a flat surface located intermediate two oppositely-inclined surfaces, and insulating material interposed between the rails and the portions of the joint that support the rails and extend alongside of the same. 105
2. A one-tie insulated rail joint provided with a base plate, constructed to be supported by a single tie and having a rail-supporting surface at approximately its center which is of less area than the portion of the base plate that rests on the joint tie, means for clamping the base flanges of the rails on said portion, and insulating material interposed between the rails and the portions of the joint that support the rails and hold them in position. 115
3. A one-tie insulated rail joint provided with a side portion that extends longitudinally along one side of the rails, a base plate of less length than said side portion whose top face is so formed that only the extreme end portions of the base flanges of the rails are normally supported by the base plate, 120
- 125

and insulating material interposed between the rails and said side portion and base plate.

4. A one-tie insulated rail joint provided with a base plate that is shorter than the portion of the joint which extends alongside of the webs of the rails, a bearing on said base plate shorter than said plate for supporting the ends of the rails, and means for 10 insulating the rails from said base plate and from the portion of the joint that extends alongside the webs of the rails.

5. An insulated rail joint, comprising a base plate for supporting the rails and a 15 side portion which extends longitudinally of the rails, a sole plate of insulating material arranged between said base plate and the base flanges of the rails, and means on the side portion of the joint that engages 20 said sole plate and prevents it from moving longitudinally of the joint.

6. An insulated rail joint, comprising a base portion for supporting the rails and a side portion which extends longitudinally of the 25 rails, a pocket in said side portion, and a sole plate of insulating material interposed between the rails and the base portion of the joint and provided with means that coöperate with the end walls of said 30 pocket to prevent longitudinal creeping of said sole plate.

7. An insulated rail joint, comprising a base plate for supporting the rails, a side portion that extends longitudinally of the 35 rails, a sole plate of insulating material on said base plate on which the base flanges of the rails rest, an upwardly-projecting flange on said sole plate, and devices on the side portion of the joint that serve as stops 40 or abutments which coöperate with the flange on the sole plate to prevent the sole plate from creeping longitudinally of the joint.

8. An insulated rail joint, comprising a 45 member provided with a base plate for supporting the rails, a portion that laps over the base flanges of the rails, a sole plate of insulating material on said base plate provided at one edge with an upwardly-projecting flange, and lugs on said member that 50 serve as stops or abutments against which

the ends of said flange strike in case the sole plate starts to creep longitudinally of the joint.

9. An insulated rail joint, comprising a 55 base plate that supports the rails, a side portion that laps over the base flanges of the rails and extends longitudinally of the rails, the top face of said base plate being provided at approximately its center with a flat rail- 60 supporting surface that is located intermediate surfaces that are inclined downwardly from the same, a sole plate of insulating material on said base plate provided at one edge with an upwardly-projecting flange, 65 and means on the side portion of the joint that coöperates with said flange to prevent the sole plate from creeping longitudinally of the joint.

10. An insulated rail joint, comprising a 70 member having a base plate for supporting the rails and a side portion integrally connected to said base plate that laps over the base flanges of the rails, a sole plate of insulating material on said base plate provided at one edge with an upwardly-projecting flange, and reinforcing and strengthening devices on said member integrally connected to said base plate and to the portion that laps over the base flanges of the 75 rails and so arranged that they serve as stops or abutments for the flange on said sole plate.

11. An insulated rail joint, comprising a 80 base plate for supporting the rails and side 85 portions arranged longitudinally of the rails on opposite sides of the same, a sole plate of insulating material arranged on said base plate and provided at one edge with an upwardly-projecting flange, means on one of 90 the side portions of the joint that coöperates with said flange to prevent longitudinal movement of the sole plate, side insulating members arranged between the rails and the side portions of the joint and provided with 95 elongated bolt openings, and bolts extending transversely through the side portions of the joint through the side insulating members and through the vertical webs of the rails.

HARRY F. ROACH.
